UNITED STATES PATENT OFFICE.

EMIL H. W. ULLRICH, OF NEW YORK, N. Y., ASSIGNOR TO THE BRYANT ELECTRIC COMPANY, OF BRIDGEPORT, CONNECTICUT, A CORPORATION OF CONNECTICUT.

ELECTRIC SWITCH.

Application filed May 12, 1921. Serial No. 468,909.

To all whom it may concern:

Be it known that I, EMIL H. W. ULLRICH, a citizen of the United States of America, residing in New York city, borough of Manhattan, in the county of New York and State of New York, have invented certain new and useful Improvements in Electric Switches of which the following is a specification.

My invention relates to electric switches, and particularly to the type of switch commonly referred to as an entrance switch, which control the connection between the wire mains and a distributing panel, although the switch may be used in any installation to which it is suited. Among the objects of my invention I may particularly mention, first, the provision of a switch having a housing of such construction that it cannot be opened while the switch is closed; second, an insulating shield so arranged that when the switch is opened the shield obstructs contact with the terminals connected to the mains; third, a simple and effective device for securing a quick break of the switch; fourth, a switch having its contacts encased at all times in insulation, through which narrow guide slots are formed to permit the entry of the switch blades through restricted passageways, thus, not only insuring a proper engagement between the switch blades and the switch contacts, but also minimizing the danger of arc formation on the opening of the switch; fifth, a simple and rugged construction of the switch-operating parts, so that they are not only readily manufactured and assembled, but also efficient in service; sixth, a compact fuse arrangement for the switch, the fuses being so positioned that they may be readily renewed, but only in the open position of the switch, and without danger to the operator; seventh, various details of construction hereinafter described or indicated in the accompanying drawings, in which

Fig. 1 is a perspective of a switch installation embodying my invention, the switch and its box casing being shown in open position;

Fig. 2 is a transverse section through the switch showing the casing and switch in closed position;

Fig. 3 is a similar view showing the casing closed, but the switch open; and

Fig. 4 is a section on the line 4—4, Fig. 3. The present switch is provided with a box-

like metal housing or casing 5 having knock-outs 6 for the admission of conduit or armored cable, through which the incoming mains 7 and outgoing leads 8 are led to or from the switch. The box may be mounted by means of bolts or screws 9 on any suitable support, for instance on the bottom of the casing (not shown) of a distributing panel. Its cover 10 is hinged at 11 to one of the box sides, and is provided with a lug 12 registering with a lug 13 on the body, both apertured at 14 to receive the shackle of a padlock 15 (Fig. 2), by which the box may be locked closed.

Within the box and resting against the bottom thereof is a connection block 16 of insulating material, such as porcelain, which is secured in position by means of suitable screws 17 taking into tapped holes in the bottom of the box. Spaced apart on the block 16 are spring clip switch contacts 18, 19, two pairs for a double-pole switch, being shown in the present drawing. These contacts have associated therewith binding-screw extensions 20 tapped to receive the screws 21 by which the mains and branch leads are mechanically secured and electrically connected. To render the construction more compact, and to interpose insulating barriers between the conductors, the wire terminals and switch contacts are let into wells 22 in the upper face of the connection block, so that only the free ends of the contact clips project above the upper face of the block, and only to a slight extent.

Overlying the connection block and housing-in the conductors thereon is an insulating cover block 23 substantially co-extensive with the connection block 16, and secured thereto by screws 24, which take into tapped rivets 25, or their equivalents. On its inner face the cover block 23 is suitably recessed at 26 to accommodate the projecting ends of the contact clips 18, 19, while slots 27 piercing the block register with the clips and form guides for the co-operating switch blades 28 and 29. The outer face of the cover block is also recessed at 30 to accommodate the fuses 31 and 32 when the switch is in closed position.

The switch blades 28 and 29, and fuses 31 and 32 are carried by a switch block 33 of insulation, which is also of substantially the same rectangular contour as the connection block and cover block. As here shown the

blades 28 and 29 are formed from strap metal. Their offset base flanges are accommodated in a recess on the inner face of the switch block 33 pierced to receive the shanks 5 of securing screw-bolts 34. Underlying the nuts on the ends of the screw-bolts and contacting with the bases of the switch blades are spring clips 35 and 36, which receive the terminal ferrules 37 of cartridge fuses, and 10 not only mechanically support the same in position, but electrically connect each fuse interposed between a pair of co-operating switch blades 28 and 29.

To open the switch a handle 38 is provided, 15 having a stem 39, which passes in through the cover 10 of the box and is connected to the outer face of the switch block 33. In order to insure a quick break between the switch blades and contacts, I mount centrally 20 on the inner face of the switch block 33 a double-arm spring plunger 40 which co-operates with a spring fork 41 mounted on the connection block 16 and projecting through the cover block 23. The spring plunger 40 25 is preferably formed from spring strap metal offset at 42 and 43 to receive the beads 44 formed at the ends of the arms of the spring fork 41. The offsets 42 and 43 are so located that when the switch is in the "on" position 30 (Fig. 2) the beads 44 of the yoke engage in the offset 42, while when the switch is open they engage in the offset 43. The switch block is thus mechanically held in both opened and closed positions by the plunger 35 40 and co-operating fork 41, while the effort required to free the plunger from the grip of the beads on the spring fork, insures a sudden outward pull of the switch block 33, and thus a quick break of the switch. The central 40 location of the plunger and fork amply spaces these parts from the conductors of the switch, and from the ferrules of the cartridge fuse, so that there is no danger of short circuit therethrough.

45 While the switch blades 28 and 29 are guided by the slots 27, and by the sides of the recess 30 in the outer face of the cover block 23, it will be noted furthermore that the switch block 33, as a whole, is guided in 50 the casing cover 10 by its relatively snug fit within the sides thereof, so that an accurate rectilinear motion of the block is insured on the switch opening and closing movements.

55 In order to lock the switch in "out of service" position, so that it cannot be closed, a hole 45 may be formed in the shank 39 of the stem of the switch handle 38 to receive the shackle of a padlock above the cover of 60 the box.

From the foregoing description it is obvious that while the casing 5-10 may be closed and locked by the padlock 15, the switch is still readily operable within the casing without opening the latter. This is an important

70 emergency provision, since immediate opening of the switch is highly desirable, should it be necessary to break the circuit by reason of any accident or defect occurring in the circuit controlled thereby. At the same time, the arrangement prevents unauthorized tampering with the switch. The hole 45 in the stem of the switch handle permits the switch to be locked "out of service," when 75 for any reason this is desired.

75 The re-fusing of the switch is rendered perfectly safe, since not only are the fuses located between the adjacent faces of the cover block 23 and the switch block 33, but it is furthermore impossible to obtain access to the interior of the switch casing until the switch has been opened. This is obvious 80 since the handle 38 is so designed as to closely approach the casing cover 10 when the switch is closed. Moreover, the plunger 14 and switch blades carried by the switch block are in engagement with the cooperating members on the connection block, and with the cover block 23 in circuit closing position, and this engagement also prevents the opening 85 of the box while the switch is closed. The switch block 33 and its associated elements, forms in effect a locking block which prevents the opening of the box until the switch block 33 has been moved outward into the 90 cover, to open-switch position. When the casing cover 10 is swung open, the block 33 is carried thereby and the fuses 31 and 32 are at a point remote from the live contacts 95 on the switch base. Moreover, the switch contacts are completely housed-in except for the narrow slots 27 in the cover block 23, which is secured to the connection block 16.

100 Obviously, the spring yoke 41 is electrically dead, and its projection beyond the face of the cover plate involves no danger.

105 The construction as a whole is simple and rugged, the porcelain parts are readily molded, the metal parts are readily shaped from sheet metal, and the box is simply designed.

110 It may also be specially pointed out that the construction is such that all the features of safety are maintained whether the power and load mains are connected to the terminals at one end or the other of the connection block. In other words, the power and load wires can be interchangeably connected to the terminals on the block without losing the safety features of construction, since when the switch is opened for re-fusing all the 115 switch blades are dead, regardless of the manner in which the wires are connected to the wire terminals.

120 Various modifications in details of structure and contour will readily occur to those dealing with the problem without, however, departing in any way from what I claim as my invention.

125 I claim—

130 1. A switch of the character described,

- comprising a connection block, switch contacts and associated terminal connections thereon, a cover block of insulating material mounted on and secured to said connection block and covering the electrical conductors thereon, said block being apertured in register with the switch contacts, together with an independent switch block of insulating material, switch blades thereon, associated 65
- 10 fuse terminals adapted to receive and electrically connect a fuse between said switch blades, a box encasing said parts, and a switch operating handle passing through the said box and connected to said switch
- 15 block for shifting the latter rectilinearly to open or close the switch, said switch box having side walls affording a guide for the switch block during its switch opening and closing movements.
- 20 2. A switch of the character described, comprising a connection block, switch contacts and associated terminal connections thereon, a cover block of insulating material mounted on and secured to said connection 70
- 25 block and covering the electrical conductors thereon, said block being apertured in register with the switch contacts, together with an independent switch block of insulating material, switch blades thereon, associated fuse terminals adapted to receive and electrically connect a fuse between said switch blades, a box encasing said parts, and a switch operating handle passing through said box and connected to said switch block for shifting 75
- 30 said switch block rectilinearly to open or close the switch, together with a plunger carried by the switch block, a co-operating spring fork associated with the connection block and cover, and engaging means between said plunger and fork to yieldingly detain the switch block against its movement to open switch position.
- 35 3. A switch of the character described, comprising a connection block, switch contacts and associated terminal connections thereon, a cover block of insulating material mounted on said connection block and covering the electrical conductors thereon, said block being apertured in register with the 80
- 40 switch contacts, together with detaining means associated with the connection block and cooperating with means associated with the switch block, means for effecting a quick break between the switch contacts and the switch blades on the opening of the switch.
- 45 3. A switch of the character described, comprising a connection block, switch contacts and associated terminal connections thereon, a cover block of insulating material mounted on said connection block and covering the electrical conductors thereon, said block being apertured in register with the 85
- 50 switch contacts, together with an independent switch block of insulating material, switch blades thereon, associated fuse terminals adapted to receive and electrically connect a fuse between said switch blades, a 90
- 55 box encasing said parts, and a switch operating handle passing through said box and connected to said switch block for shifting said switch block rectilinearly to open or close the switch, together with spring 95
- 60 means insulated from the conductors and comprising cooperating elements on the connection block and switch block for effecting a quick break between the switch contacts 100
- and the switch blades on the opening of the switch.
4. A switch of the character described, comprising a connection block, switch contacts and associated terminal connections thereon, a cover block of insulating material mounted on said connection block and covering the electrical conductors thereon, said block being apertured in register with the switch contacts, together with an independent switch block of insulating material, switch blades thereon, associated fuse terminals adapted to receive and electrically connect a fuse between said switch blades, a box encasing said parts, and a switch operating handle passing through said box and connected to said switch block for shifting 105
5. An electric switch comprising a connection block, terminals and switch contacts carried thereby, an insulating cover plate overlying said terminals and switch contacts and apertured in register with the latter to permit the insertion of switch blades therethrough into engagement with the contacts on the connection block, in combination with an insulating switch block, switch blades mounted thereon in register with the switch contacts, associated fuse terminals adapted to support a fuse between the switch and 110
6. An electric switch comprising a connection block, terminals and switch contacts carried thereby, an insulating cover plate overlying said terminals and switch contacts and apertured in register with the latter to permit the insertion of switch blades therethrough into engagement with the contacts on the connection block, in combination with an insulating switch block, switch blades mounted thereon for engagement with the switch contacts on the connection block, fuse 115
7. An electric switch comprising a connection block, terminals and switch contacts carried thereby, an insulating cover plate overlying said terminals and switch contacts and apertured in register with the latter to permit the insertion of switch blades therethrough into engagement with the contacts on the connection block, in combination with an insulating switch block, switch blades mounted thereon for engagement with the switch contacts on the connection block, fuse 120
8. An electric switch comprising a connection block, terminals and switch contacts carried thereby, an insulating cover plate overlying said terminals and switch contacts and apertured in register with the latter to permit the insertion of switch blades therethrough into engagement with the contacts on the connection block, in combination with an insulating switch block, switch blades mounted thereon for engagement with the switch contacts on the connection block, fuse 125

In testimony whereof I have signed my name to this specification.

EMIL H. W. ULLRICH.

Certificate of Correction.

It is hereby certified that in Letters Patent No. 1,482,958, granted February 5, 1924, upon the application of Emil H. W. Ullrich, of New York, N. Y., for an improvement in "Electric Switches," an error appears in the printed specification requiring correction as follows: Page 3, line 14, claim 1, after the article "the," insert the words *top of*; and that the said Letters Patent should be read with this correction therein that the same may conform to the record of the case in the Patent Office.

Signed and sealed this 18th day of March, A. D., 1924.

[SEAL.]

KARL FENNING,
Acting Commissioner of Patents
